(57) **CLAIM**

The ornamental design for an electroporation gasket, as shown and described.

DESCRIPTION

FIG. 1 is a front, top, left perspective view of an electroporation gasket, showing the new design;

FIG. 2 is a rear, bottom, right perspective thereof;

FIG. 3 is a front elevation view thereof; wherein the rear elevation view is identical thereto;

FIG. 4 is a left side view thereof; wherein the right side view is identical thereto;

FIG. 5 is a top plan view thereof; and,

FIG. 6 is a bottom plan view thereof.

The broken lines of even length depict portions of the electroporation gasket that form no part of the claimed design.
